UNITED STATES PATENT OFFICE.

WILLIAM B. HODGE, OF CHARLOTTE, NORTH CAROLINA, ASSIGNOR TO STUART W. CRAMER, OF CHARLOTTE, NORTH CAROLINA.

HUMIDIFYING, HEATING, AND VENTILATING SYSTEM.

1,147,244.

Specification of Letters Patent. Patented July 20, 1915.

Application filed May 6, 1913. Serial No. 765,749.

To all whom it may concern:

Be it known that I, WILLIAM B. HODGE, a citizen of the United States, residing at Charlotte, in the county of Mecklenburg and 5 State of North Carolina, have invented certain new and useful Improvements in Humidifying, Heating, and Ventilating Systems; and I do hereby declare the following to be a full, clear, and exact description of 10 the invention, such as will enable others skilled in the art to which it appertains to make and use the same.

This invention relates to humidifying, heating and ventilating systems and has for 15 its object to provide such a system whereby the atmosphere in a mill or other room can be maintained at different temperatures or different humidities in two sections of the room, and whereby, for instance, a cool, 20 moist condition is obtainable in the lower level of the room and in the upper levels a drier and warmer condition.

The invention consists in certain improvements which will be hereinafter described 25 and fully pointed out in the claims.

In the accompanying drawings which form part of this specification:—Figure 1 represents a sectional perspective elevation of an ordinary room with a loom, such as is 30 used in weaving ordinary cloth. Fig. 2 represents a sectional elevation of the end of the loom and the floor of the mill, showing the distributing pipe. Fig. 3 represents a sectional end elevation of Fig. 2, on line 35 3—3 and Fig. 4 represents a plan view of the distributor.

Reference being had to the drawings and the designating characters thereon, 1 indicates a duct of galvanized iron or other suitable material for conveying air from a fan or other source of supply, not shown, heated and moistened to any degree desired, across the mill, and thence by lateral ducts 1' along or through the mill directly underneath the floor or underneath the line of looms or other equipment which it is desired to humidify. 2 indicates a similar duct leading from the same or from another fan for the purpose of carrying humidified or 45 heated or cooled air, depending on the season of the year, to the upper part of the room and thence through a distributing pipe extending the length of the mill provided with lateral outlets 4.

50 3 indicates a temperature and humidity

controller through which the air from the duct 1 is forced and passed over thermo-responsive members, and by means of which both the temperature and humidity of the air entering the duct 1 is controlled to any 60 desired degree. Such a humidity controller is illustrated and described in application for United States Letters-Patent, Serial No. 607,849, as well as in Patent No. 856,944, June 11, 1907, and does not need further 65 description here.

5 indicates the wall of the mill building in which the equipment is designed to be operated.

6 indicates a loom, the warp threads of 70 which it is desired to keep moistened so as to prevent breakage of the warp and produce better, smoother, nicer running work.

7 indicates the beam on which the warp threads are wound.

8 indicates the outlet from duct 1' by means of which the humidified and treated air from duct 1 is led up through the pipe 9 and discharged against the beam 7.

10 indicates a regulator similar to 3, and 80 is for the purpose of controlling the humidity and temperature of the air in the room, more especially that supplied through duct 2.

It is well known that in weaving operations, and especially in the operation known 85 as jacquard weaving, that there is great advantage or gain in keeping the warp threads damp and moist, but this gain is often necessarily sacrificed on account of the detrimental effects that occur in the paper card

90 patterns and other moisture sensitive parts 95 of the jacquard attachment. Changes in temperature and humidity about a jacquard are extremely undesirable and render perfect work difficult of attainment. On the other hand, considerable moisture around the warp threads increases production and produces a far superior class of goods. Hence is seen the desirability of maintaining a dry condition of the atmosphere in the 100 upper portion of the room where the jacquard section is placed, and a moist stratum of air in the lower part of the room where the warp beams and threads are located.

It is seen, therefore, by this double distribution of air that I have made provision for introducing through duct 1 and its lateral branches, and discharging underneath each loom and directly against the beam and warp threads, a blast of air which is con- 105

trolled both as to its relative humidity and temperature by means of automatic regulator 3. Furthermore, in order to maintain a drier and a somewhat warmer atmospheric condition in the upper part of the room, air is forced through duct 2 and distributed overhead and the relative humidity and the temperature of that air maintained at any desired condition by means of the 5 regulator 10. With the adjustments that are provided on each of the regulators of this type, it is therefore evident that I can discharge air against the warp at any desired humidity and temperature, depending 10 upon the setting of the regulator 3, and air into the upper part of the room at any desired humidity and temperature by means 15 of the setting of the regulator 10.

It is evident, that this method of distribution is not necessarily confined merely to 20 rooms or factories wherein the weaving operation is carried on, or even limited to the use for looms; there are other manufacturing conditions where it is desirable to 25 maintain different atmospheric conditions at the lower part of the room than at the upper part of the room. This invention therefore, is not limited merely to rooms where looms are operated, but is useful in 30 any location where different atmospheric conditions are desired in different parts of the room. It is further evident that it is not essential that the one distributing duct should be located underneath the loom or 35 beneath the floor. It could be located above the machinery, provided suitable outlets or branches were provided and the air distributed from those outlets near the floor or against the warps.

40 The essential feature of this invention is the multiple distribution of differently conditioned air currents.

Having thus fully described my invention, what I claim is:

- 45 1. In a ventilating system, means for supplying air of different qualities in different planes or strata, and means for automatically regulating each supply of air.
2. In a ventilating system, means for 50 supplying air of predetermined humidity

and temperature in different planes or strata, and separate means for automatically regulating each supply of air.

3. A duplex ventilating system comprising a plurality of ducts for distributing air 55 currents having different heat and moisture properties, and means for automatically controlling the relative humidity and temperature of air supplied by each system.

4. A duplex ventilating system comprising an upper duct and a lower duct, said ducts being adapted to carry air currents having different heat and moisture properties, and means for automatically controlling the relative humidity and temperature 65 of the air in each duct.

5. In a duplex ventilating system comprising a plurality of ducts, a humidity and temperature control for each duct, and means for distributing the air from each 70 duct in different parts of a room or building.

6. In a humidifying and heating system, means for distributing tempered air in a predetermined plane, and means for distributing tempered air in a lower plane, and 75 means for automatically controlling the humidity and temperature in each of said currents of air.

7. In a combined upper and lower heating and humidifying system, means for distributing the air from the upper system generally, and means for distributing the air from the lower system locally, and means for controlling the humidity and temperature of each current of air. 80

8. In a duplex humidifying and heating system, means for supplying tempered air to the upper part of a room or building, and means for supplying air with different atmospheric conditions to a lower part of the 90 room or building, and means for controlling the humidity and temperature of the air in each system.

In testimony whereof I affix my signature in presence of two witnesses.

WILLIAM B. HODGE.
